CLAIM

The ornamental design for perforated paper blank for color matching strips, as shown and described.

DESCRIPTION

FIG. 1 is a front view of a perforated paper blank for color matching strips showing our new design;

FIG. 2 is a top edge view of the perforated paper blank for color matching strips showing our new design, the bottom edge view being identical;

FIG. 3 is a right side edge view of the perforated paper blank for color matching strips showing our new design, the left edge view being identical; and,

FIG. 4 is a back view of the perforated paper blank for color matching strips showing our new design.

The dot, dash broken lines shown in FIGS. 1 and 4 of the drawing represent perforations.
